UNITED STATES PATENT OFFICE.

EDWARD HANSON, OF CHICAGO, ILLINOIS.

BERTH CONSTRUCTION.

1,250,307.

Specification of Letters Patent. Patented Dec. 18, 1917.

Application filed March 31, 1917. Serial No. 158,873.

To all whom it may concern:

Be it known that I, EDWARD HANSON, a citizen of the United States, and a resident of the city of Chicago, county of Cook, and 5 State of Illinois, have invented certain new and useful Improvements in Berth Constructions, of which the following is a specification.

My invention relates to improvements in 10 berth attachments especially adapted for use in sleeping cars, and has for its object the provision of an improved construction of this character for mounting and arranging the curtains therefor, for preventing 15 upward swinging of the upper berth, and preventing accidental falling from said upper berth.

The invention consists in the combinations and arrangements of parts hereinafter 20 described and claimed.

The invention will be best understood by reference to the accompanying drawings forming a part of this specification, and in which,

25 Figure 1 is a face view of an ordinary sleeping car berth equipped with means embodying my invention,

Fig. 2, an enlarged transverse section taken through the upper portion of said 30 berth,

Fig. 3, an enlarged detail view illustrating a latch arrangement employed in the construction,

Fig. 4, a face view illustrating the mounting for the curtain rod for the upper berth,

Fig. 5, an enlarged sectional view illustrating locking means employed for locking the curtain rod supports in folded positions,

40 Fig. 6, an enlarged section taken on line 6-6 of Fig. 4.

Fig. 7, a view taken at right angles to Fig. 6,

Fig. 8, a section taken on line 8-8 of 45 Fig. 4, and

Fig. 9, a section taken on line 9-9 of Fig. 5.

The preferred form of construction, as 50 illustrated in the drawings, comprises a tubular curtain rod 10 mounted at the free ends of two swinging supporting arms 11 hinged at 12, adjacent the roof of the car, and arranged to swing downwardly to the dotted line position indicated in Fig. 2, over 55 the usual upper berth 13 of the car. Each of the arms 11 is provided with an upstand-

ing notched lug 14 adapted to engage a spring catch 15 secured to the roof of the car and arranged to detachably hold the arms 11 in distended positions, as indicated 60 in full lines in Fig. 2. The arms 11 are provided with depending brackets 16 in which are pivoted rigid supporting rods 17 flattened at their lower ends, and provided with rectangular notches 18 adapted to fit 65 over lugs 19 on corresponding brackets 20 secured to the free or swinging edge of the berth 13. A latching block 21 is pivotally mounted on each of the brackets 20 in position to swing across the outer end of the 70 corresponding lug 19 to detachably lock the corresponding support 17 in place, as best shown in Figs. 6 and 8.

By this arrangement, it will be observed, 75 that the curtain rod 10 may be readily swung to operative relation with the upper berth 13 and rigidly locked in such relation by means of the supports 17, said supports 17 also serving as rigid locks to prevent upward swinging of said upper berth, the curtain 80 rod then acting as a solid abutment for the purpose.

Latch members 22 are slidably mounted 85 on rod 10, adjacent the center thereof, each of said latch members being provided with screws 23 sliding in slots 24 in said rod, compression springs 22' yieldingly holding 90 said latch members in operative positions. Each of the latch members 22 is provided with a retaining socket 25 adapted to receive and hold the lower end of the corresponding support 17, as indicated in dotted 95 lines in Fig. 5. By this arrangement, it will be observed, that the supports 17 may be readily folded upwardly against the under side of the rod 10, and detachably locked in folded position by means of the latch members 22.

A curtain 26 is provided for the upper 100 berth 13, being detachably supported upon hooks 27 slideable on rod 10, the lower edge of the curtain 26 being provided with straps 28 secured to a securing bar 29 arranged, as indicated, at the free edge of berth 13. A separate curtain 30 is provided for the 105 lower berth, being provided at its upper end with straps 31 by means of which it may be detachably suspended on a supporting bar 32 also mounted on the upper berth 13, as indicated.

110 By this arrangement the curtains for the two berths are independent of each other,

thus avoiding disturbance of the occupant of one berth by the occupant of another. Likewise the straps 28 tend to prevent accidental falling from the upper berth.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention what I claim as new and desire to secure by Letters Patent is:

1. The combination with an upwardly swinging berth member and an abutment 20 member, of a rigid rod pivoted to one of said members and detachably connected with the other, substantially as described.

2. The combination with a sleeping car or the like having an upwardly swinging berth, 25 of one or more rigid locking rods pivotally mounted on said car and detachably connected with said berth to prevent upward swinging thereof, substantially as described.

3. The combination with a sleeping car or 30 the like having an upwardly swinging berth, of downwardly swinging arms mounted on said car projecting over said berth; and a curtain rod at the outer ends of said arms, substantially as described.

35 4. The combination with a sleeping car or the like having an upwardly swinging berth, of downwardly swinging arms mounted on said car projecting over said berth; a curtain rod at the outer ends of said arms; and 40 latching means for holding said arms in extended positions, substantially as described.

45 5. The combination with a sleeping car or the like having an upwardly swinging berth, of downwardly swinging arms mounted on said car projecting over said berth; a curtain rod at the outer ends of said arms; and rigid supports on said rod engaging said berth, substantially as described.

Copies of this patent may be obtained for five cents each, by addressing the "Commissioner of Patents, Washington, D. C."

6. The combination with a sleeping car or the like having an upwardly swinging berth, 50 of downwardly swinging arms mounted on said car projecting over said berth; a curtain rod at the outer ends of said arms; latching means for holding said arms in extended positions; and rigid supports on said rod 55 engaging said berth, substantially as described.

7. The combination with a sleeping car or the like having an upwardly swinging berth, 60 of downwardly swinging arms mounted on said car projecting over said berth; a curtain rod at the outer ends of said arms; and rigid supports on said rod engaging said 65 berth and folding against said rod, substantially as described.

8. The combination with a sleeping car or the like having an upwardly swinging berth, 70 of downwardly swinging arms mounted on said car projecting over said berth; a curtain rod at the outer ends of said arms; latching means for holding said arms in extended positions; and rigid supports on said rod engaging said berth and folding against said rod, substantially as described.

9. The combination with a berth, of a 75 curtain rod coöperating therewith; and rigid supports hinged to said curtain rod engaging said berth and foldable against said rod, substantially as described.

10. The combination with a berth, of a 80 curtain rod coöperating therewith; rigid supporting members hinged to the ends of said rod to fold upwardly against the same; spring locking members at the center of said rod arranged to detachably engage the ends 85 of said supports; and detachable connections between the lower ends of said supports and said berth, substantially as described.

In testimony whereof I have signed my name to this specification in the presence of 90 two subscribing witnesses.

EDWARD HANSON.
